723,735. Divided and this application July 22,
1936, Serial No. 91,810

8 Claims. (Cl. 181—48)

This invention relates to mufflers of the kind used in silencing the exhaust of internal combustion engines.

One of the objects of this invention is to provide a muffler which is built in two separate sections or units and in which a resonator chamber of one section or unit is connected by means of a relatively small tube with a resonator chamber of another section or unit to produce a resonator effect equivalent to that of a much longer single chamber. Another object is to provide a muffler comprising a plurality of short sections or units which are connected in such a manner as to silence low frequency sound waves which would otherwise require a much longer single resonator chamber. Further objects of the invention will appear from the following description and claims.

This is a division of our pending application No. 723,735, filed May 3, 1934.

20 In the accompanying drawing:

Fig. 1 is a longitudinal central sectional view of a portion of a muffler, and Fig. 2 is a similar view of the remaining portion of a muffler embodying this invention.

25 Fig. 3 is a transverse sectional view, on line 3—3, Fig. 2.

In the design of mufflers for silencing the exhaust of internal combustion engines, it frequently happens that the engine produces low sounds having low frequency sound waves which require long resonator chambers to silence such sounds by destructive interference. In some cases, mufflers cannot be made of sufficient length to provide resonator chambers of the required 35 lengths because of lack of a continuous space of sufficient length on the chassis of a vehicle to accommodate mufflers of such length, and in some cases, it is not economical to make mufflers of the required length. In accordance with this invention, mufflers can be made of relatively short units or sections which can be connected in such a manner as to produce the effect of resonator chambers of greater length than the length of any one section or unit.

40 45 In Figs. 1 and 2 is shown a muffler formed in three sections A, B and C, but it will be understood that the muffler may have only two sections or more than three sections, if desired. The sections may be of any suitable construction, those 50 shown in the drawings illustrating merely one embodiment of this invention.

The section or unit A of the muffler is provided with an outer shell 5 provided at one end thereof with a head 6 having formed thereon a tubular portion 7 to which an exhaust pipe leading from

the engine may be suitably secured in the usual manner. At the other end, the outer shell 5 is provided with an end head 8. The muffler is provided with an inner shell or conduit 9 terminating at one end in a tubular extension 10 of the head 8 and having the other end thereof supported by means of a baffle or intermediate head 11 from an intermediate shell 12. Other baffles or intermediate heads 15 and 16 connect the inner shell or conduit with the intermediate shell 12, and one end of the intermediate shell may be telescoped within an annular shoulder 17 formed on the head 6. The inner shell or conduit is provided with suitable perforations or apertures 18 of any suitable or desired form, these apertures 15 being arranged in groups lengthwise of the inner conduit.

The construction described results in the formation of two high frequency resonator chambers 20 and 21 formed between the inner conduit 20 and the intermediate shell, and a low frequency resonator chamber 22 formed partly between the outer and intermediate shells and partly between the outer shell and the inner shell or conduit 9. This latter chamber silences sound waves of lower frequency than those silenced by the high frequency resonator chambers 20 and 21.

The second section or unit B of the muffler includes an outer shell 25 and a head 26 having a tubular extension 27 which may be connected 30 by means of a sleeve or short tube 28 with the tubular extension 10 of the head 8 of the section A of the muffler. This section of the muffler is also provided with an inner shell or conduit 30, one end of which telescopes within the tubular 35 portion 27 of the head 26, and the other end of which telescopes within a tubular extension 31 of a head 32, Fig. 2. This section or unit of the muffler is also provided with an intermediate shell 33, one end of which is supported by means 40 of an annular shoulder 34 of the head 32, Fig. 2, and the other end is supported by a baffle or intermediate head 35 connecting the intermediate shell with the outer shell 25, the baffle having a series of apertures 36. The section or unit B is 45 also provided with baffles or intermediate heads 37 and 38 extending between the conduit 30 and the intermediate shell 33. The inner conduit is provided with suitable apertures 39 also arranged in groups, one group of these apertures establishing communication between the conduit and a high frequency chamber 40 formed between the baffles 37 and 38 and another group of apertures establishing communication with a high frequency chamber 41 formed between the baffle 38 50 and 55

and the head 32 of this section of the muffler. At the front end of the section B of the muffler is formed a chamber 43 between the inner and intermediate shells and the front end of this chamber opens into a chamber 44 formed between the head 26 and the baffle 35. It will be noted that the front end of the intermediate shell 33 extends about an imperforate portion 45 of the inner shell or conduit which forms with the intermediate shell a bottle neck or passage through which sound waves may pass from the chamber 43 into the chamber 44 and thence through the apertures 36 of the baffle 35 into a low frequency resonator chamber 46 formed between the intermediate and outer shells and extending substantially throughout the length of the section B of the muffler. Any other bottle neck or other means for establishing communication between the chamber 46 and the inner shell or conduit for conducting sound waves from the main stream of exhaust gas to the resonator chamber 46 may be employed.

The third unit or section C of the muffler has an outer shell 50, an inner conduit 51 and an intermediate shell 52, the outer shell and the conduit or inner shell being suitably supported on heads 53 and 54. The head 54 has a tubular extension connected by means of a short sleeve or tube 55 with the tubular extension 31 of the head 32, and the discharge end of the conduit or inner shell 51 terminates in an annular shouldered portion 56 of the head 54. This head is preferably also provided with a tubular portion 57 to which the usual tail pipe may be connected. The inner and intermediate shells are connected by baffles or intermediate heads 60 and 61 to form three high frequency chambers 63, 64 and 65. The outer and intermediate shells are also connected by means of baffles or intermediate heads 66 and 67 which form the space between these two shells into chambers 68 and 69, the baffle 67 having apertures 70 through which sound waves may pass from the apertures of that portion of the inner shell or conduit 51 which extends beyond the end of the inner shell 52.

The sections or units B and C of the muffler are shown in the accompanying drawing as connected in such a manner that the outer chamber 46 of the section B may operate in conjunction with the chamber 68 of the section C of the muffler to produce a composite resonator chamber having silencing effect upon low frequency sound waves which is equivalent to the silencing effect which would be produced in a chamber of greater length than any of the sections of the muffler. This may be accomplished in any suitable or desired manner, and in the construction illustrated, a tube or pipe 75 of relatively small diameter is used for this purpose. This tube is suitably secured in flanged openings 76 and 77 formed in the heads 32 and 53 of the sections B and C of the muffler. If desired, a number of such tubes or pipes may be used. As a result of this construction, sound waves from the main current of gases in the conduit 30 pass through the chamber 43 and the bottle neck 45 and through apertures 36 of the baffle 35 into the chamber 46 of the section B of the muffler, and then through the tube or pipe 75 into the chamber 68 of the section C of the muffler, and such sound waves after passing into these chambers are returned in the reverse direction into the inner conduit to silence certain sound waves by destructive interference.

The muffler described has the advantage that it is of the straight through type in which the

gases pass from one end of the muffler to the other end thereof without change of direction and without encountering any serious resistance to their flow. High frequency sound waves are silenced by means of the several high frequency resonator chambers formed between the inner and intermediate shells. Sound waves of somewhat lower frequencies are silenced in the chambers 22 and 69, and sound waves of very low frequencies are silenced by the combined action of the chambers 46 and 68. The muffler is also readily adaptable for use in connection with engines of different designs, since the several chambers may be made of greater length by locating the baffles as may be desired. For example, the baffle 66 in section C of the muffler may be positioned in different locations lengthwise of the space between the outer and intermediate shells of this section of the muffler so that the length of the chambers 68 and 69 may be varied to enable these chambers to silence sound waves of different frequencies. The length of the bottle neck 45 may also be varied as desired to further adapt the chambers 46 and 68 to operate on different wave lengths. The construction described thus forms double bottle neck chamber in that the pipe 75 also forms with the chamber 68 a bottle neck type of resonator chamber and variations in the length of the pipe 75 also varies the frequencies of sound waves silenced by the 30 chambers.

The construction described is also readily adaptable to various chassis designs since the sleeves 28 and 35 connecting adjacent sections may, of course, be made of any desired length. 35

We claim as our invention:

1. A muffler comprising a plurality of sections and having a substantially continuous gas passage common to said sections, a pair of said sections arranged adjacent to each other being provided with nested shells and heads forming resonance chambers, and a relatively small passage extending from one section to the other and connecting the resonance chambers of adjacent sections to produce a composite resonance chamber. 45

2. A muffler comprising at least two sections and having a substantially continuous inner passage for gases and sound waves extending through said sections, each section being provided with intermediate and outer shells surrounding said inner passage and forming about said passage intermediate and outer chambers, the outer chamber of one of said sections being connected to receive sound waves from said passage and the outer chamber in another section having no connection with the inner chamber or passage in its section, and a relatively small tube connecting the outer chambers of adjacent sections. 55

3. A muffler comprising at least two sections and having a substantially continuous straight passage for gases, each section having a pair of shells arranged one within the other and forming between them a chamber, the chamber of one of said sections being in communication with said passage, and a passage extending from one section to the other and connecting said chambers. 65

4. A muffler having a section provided with a passage for gases, a shell and baffles forming a resonator chamber communicating with said passage to permit sound waves to pass to and from said passage and chamber, a second section formed separately from said first section and having a shell and baffles forming a chamber, and a tube connecting said chambers of said sections 70 75

to form said chambers into a composite resonator chamber.

5. A muffler having a section, comprising a conduit for gases and having perforations, a shell surrounding said conduit and receiving sound waves through said perforations, another shell arranged about said last shell and forming therewith a resonator chamber communicating with said conduit to permit sound waves to enter said 10 conduit, a second section having walls forming a substantially closed chamber therein, and a tube connecting said last mentioned chamber and said resonator chamber to form a composite resonator chamber.

15. 6. A muffler comprising at least two sections, one of said sections having a conduit for gases, provided with perforations arranged in groups, a shell surrounding a group of perforations and also surrounding an imperforate part of said conduit, a second shell arranged about said first shell and forming therewith a chamber communicating with said conduit through the space between said first shell and said imperforate part of said conduit to form a bottle neck type of resonator chamber, the other of said sections having walls forming a substantially closed chamber,

and a tube connecting said last mentioned chamber with said resonator chamber to form another bottle neck resonator chamber communicating with said first bottle neck resonator chamber.

7. A muffler formed of at least two sections, 5 each of which has walls independent of the walls of the other section and forming a resonator chamber in each section, a conduit for conducting gases and sound waves, means for conducting sound waves from said conduit to one of said 10 chambers, and a tubular member extending from one section to the other and connecting said resonator chambers.

8. A muffler formed of at least two sections, 15 each of which has walls independent of the walls of the other section and forming a resonator chamber in each section, a conduit for conducting gases and sound waves, means for conducting sound waves from said conduit to one end of one 20 of said resonator chambers, and a tubular member extending from the other end of said last mentioned resonator chamber to one end of the other resonator chamber in the other section.
